DESIGN FOR A BOTTLE

Frank T. Kessler, Philadelphia, Pa.

Application December 19, 1933, Serial No. 50,112

Term of patent 14 years

To all whom it may concern:

Be it known that I, FRANK T. KESSLER, a citizen of the United States, residing at Philadelphia, in the county of Philadelphia and State of Pennsylvania, have invented a certain new, original, and ornamental Design for a Bottle, of which the following is a specification, reference being had to the accompanying drawing, forming part thereof.

Figure 1 represents an elevational view, in perspective (at a slight angle from above) showing a full view of one of the faces of the bottle embodying the design for bottle of my invention.

Figure 2 represents a similar elevational view in perspective (at a slight angle from above) taken at 45° to the view of Figure 1, showing two of the main faces and the intervening auxiliary faces.

Figure 3 represents a top plan view of the design for bottle embodying my invention.

I claim:

The ornamental design for a bottle, as shown and described.

FRANK T. KESSLER.
